WELL CASING PERFORATOR

Frank R. Rutherford and Ralph M. Ridley,
Whittier, Calif.

Application February 25, 1938, Serial No. 192,532

15 Claims. (Cl. 164—0.5)

This invention relates to mechanism for perforating the casing in a well bore, and more particularly to a perforating gun which discharges projectiles by detonating a charge of explosive 5 with sufficient force to pass through the casing and into the formation outside thereof.

It is common practice incident to placing oil wells on production, to perforate the well casing in the productive zone. This is frequently done 10 by lowering some form of mechanical perforating device into the casing to the place where the perforations are desired, and then manipulating the machine from the surface of the ground to perform the perforating operation. Due to the 15 necessity of remotely controlling such devices, satisfactory operation is difficult. For this reason, and also because to more effectively start production, it is desirable to break up the formation surrounding the casing, perforating guns 20 which are readily controllable from the surface of the ground and which fire a bullet or projectile through the wall of the casing and into the formation, have been suggested.

Such guns have usually been characterized by 25 an electrical firing mechanism, and one or more bores for directing the projectiles through the casing. These perforating guns have also been lacking in flexibility, that is, they were capable of making a definite number of perforations only, 30 and if more were required, the gun had to be removed from the well and another one inserted.

It is a principal object of this invention to 35 provide a perforating gun which covers a zone of considerable depth, and which comprises sections which may be successively lowered into the well and fired as conditions dictate, without the necessity of any withdrawals.

Another object of this invention is the provision 40 of a perforating gun in which the explosive discharging the projectile is detonated by a firing pin, operating by impact on the gun.

It is another object of this invention to provide 45 a multi-section perforating gun, in which the successive sections are adapted to slide downwardly on the sand line, this serving to guide them in the casing, each section acting in conjunction with the stationary section below as a detonator.

A still further object of this invention is the 50 provision of a perforating gun having an inclined barrel, whereby the length of the barrel for the travel of the projectile is increased to improve the efficiency of operation, and to impart greater velocity to the projectile.

55 A still further object of this invention is the

provision of means, whereby a perforating gun of one size may be used to perforate various size casings.

This invention possesses many other advantages, and has other objects which may be made 5 more easily apparent from a consideration of several embodiments of the invention. For this purpose there are shown a few forms in the accompanying drawings, which form part of the present specification. These forms will now be 10 described in detail, illustrating the general principles of the invention; but it is to be understood that this detailed description is not to be taken in a limiting sense, since the scope of the invention is best defined by the appended claims. 15

Referring to the drawings:

Figure 1 is a longitudinal section taken along a plane passing through the axis of one form of gun;

Figs. 2 and 3 are sections taken along corresponding numbered planes of Fig. 1; 20

Fig. 4 is a diagram, showing the perforator in use in a well;

Fig. 5 is a view similar to Fig. 1, but of a modified form of the invention; 25

Fig. 6 is a cross-section as seen on plane 6—6 of Fig. 5;

Fig. 7 is a section similar to Fig. 6, but of another modification of the invention;

Fig. 8 is a longitudinal section of an adaptor 30 sleeve;

Fig. 9 is a plan view of the adaptor sleeve; and Figs. 10 and 11 are details of the projectile.

Referring to Figs. 1, 2 and 3, a form of perforating gun is shown therein having a cylindrical body 15 provided with a pair of oppositely directed barrels 16 and 17, oblique to the vertical axis of the body. The ends of the body are provided with detachable caps 18 and 19 which serve to confine cartridges 20 and 21 in the barrels 16 and 17 respectively. Each cap carries 35

firing mechanism, indicated by 22, which is adapted to discharge the associated cartridge upon receiving a blow directed generally in axial direction with respect to the body. An opening 40 or passage 23 is provided in the body to accommodate a cable or sand line 24 which serves to guide the apparatus when it is being placed in the well casing, and also to remove it when desired.

The entire gun is enclosed in a fluid tight 45 casing 25 of light sheet metal, which serves to exclude air and water from the cartridges and the firing apparatus until such time as the gun is discharged.

In Figure 4, the well casing 26 is to be perfo- 50

55

rated, and a perforating gun 27 is shown suspended in the casing at the place where the lowermost perforations are wanted by means of the cable 24 which may conveniently be the usual sand line of a drilling outfit. The cable has a member 28 secured to it for supporting the gun 27, and suitable weights 29 may be also attached to the cable if desirable, to assist in lowering it into the well.

10 The perforating gun may be placed on support 28 and lowered into the well along with the cable 24 to the desired level, in position to be later discharged. Or the cable and support may be positioned in the well first, after which the gun is 15 placed on the cable and allowed to follow it downwardly until it reaches member 28. Due to the well liquid which is always present, the gun will not fall with excessive speed, but will, nevertheless, strike member 28 with enough force to 20 distract the casing 25 and operate the firing mechanism 22 at the lower end.

An additional gun, such as 30, may then be placed on the sand line and allowed to ride into the well. When this gun strikes the gun 27, the 25 firing mechanism in its lower end, as well as that in the upper end of gun 27, will be actuated to fire their associated cartridges. In case the gun 27 has been lowered with the sand line, the impact of the succeeding gun 30 will also cause 30 the lower cartridge in gun 27 to be fired. Additional guns may be placed on the sand line and allowed to fall in the well, operating the firing mechanism in contacting ends in the same way until a desired length of casing has been 35 perforated, or until the well production indicates a sufficient amount of perforating. After this, all of the guns can be removed together from the well with the same sand line. From the foregoing it will be apparent that there is great flexibility of operation, since the extent of the perforating desired can be determined as the work progresses. Further, it is not necessary to remove the cable or any of the guns from the well 40 until the work is completed.

45 Reverting to the details of construction, each of the barrels 16 and 17 which are pressed into the body 15 has a bore 33 which may be suitably rifled. The cartridges 20 and 21 may be of any type usually employed for this class of work, but are provided with a novel type of projectile 34, as 50 shown in Figs. 10 and 11, having a relatively sharp advancing point 35. For better penetrative ability, this point is placed preferably at or near the edge of the projectile or bullet 34. The adjacent sloping surfaces 31 that define the point, may intersect along the line 32.

Caps 18, 19 are secured to the body by a 55 tapered thread 36 and engage the frusto-conical ends 43 of the body, serving as breech blocks to hold the cartridges in position. They may be 60 easily removed and replaced, permitting the insertion of new cartridges. The firing mechanisms 22 each include a firing pin 37 slidable in the cap, and a rectangular firing block 38 having a convex outer surface. The firing block 38 is 65 accommodated in a rectangular recess in the cap and is urged outwardly by a pair of flat springs 39, screw 40 serving to limit outward movement of block 38. It will be apparent that a blow on block 38 will drive the block inwardly, causing pin 37 to explode the cartridge. In order that the gun may be caused to closely follow cable 24 as it drops in the well, a closure 41 is provided for recess 23. It may be conveniently secured to the body by screws 42.

It will be noted that casing 25 follows the configuration of the body as far as this recess is concerned, whereby all openings in the casing are eliminated, and at the same time the gun may be readily placed on the cable. It is to be understood that this casing is of sufficiently light material to be readily distorted by the impact of the falling gun so that the firing mechanism will operate. Further, it will easily rupture when the cartridge is discharged, so as not to impede the 10 gases formed thereby, or the passage of the projectile.

For the most effective operation of the gun, the place where the projectile leaves the bore of the barrel should be fairly close to the wall of the casing. Obviously this can be readily accomplished by having a gun with a body of suitable diameter for each size casing. However, by the use of an adaptor, as shown in Figs. 8 and 9, a small size gun may be effectively used in large 15 sized casing. By providing a variety of adaptors having different external diameters but common internal diameters, a small diameter gun may be used in a number of larger casings. This is a decided advantage, since the adaptors are simple 20 and inexpensive. The adaptor is used to form an extension barrel.

The adaptor may take the form of a ring 45, divided in halves 46 and 47 along an axial plane. The inside of the ring fits closely around the casing 25 of the gun, the outside diameter of the ring being such as to give proper clearance between the adaptor and well casing 48. Each half of the ring is provided with an oblique hole such as 49, which forms a continuation or extension of the corresponding bore 33. The adaptor ring is assembled around the gun after the latter has been placed on the line 24, screws 50 accommodated in tapped holes 44 formed in gun body 15 serving to accurately secure the adaptor 40 in position.

It may be desirable to have a gun unit capable of handling more cartridges than the form just described. Figs. 5 and 6 show such a form having three barrels, but this is illustrative only, as there may be more than three. The body 51 is cylindrical as before, and has the pressed in barrels 52, 53 and 54, provided with rifle bores, making a less acute angle with the body axis. Each barrel is adapted to receive a cartridge 63, 64 or 65 which may be of the same type as before 50 and is held in place by a breech block 55, 56 or 57. Each breech block is detachably secured to the body by screws 58, thus providing access to the gun barrel for reloading. The upper breech block 55 provides a vertical guide for a firing pin 59 adapted to fire the upper cartridge 63 upon downward vertical movement of the pin relative thereto. This movement may be imparted to it by head 60, slidably mounted in a recess 60 formed in the upper end of the body 51. Springs 62 urge the head outwardly, screw 61 serving to limit this outward movement. Breech block 56 also has a firing pin 66 sliding supported therein and adapted to fire cartridge 64 upon being forced downwardly. Firing pin 66 has a head 63 with a flat upper surface 64 which is at substantially a right angle with the axis of the body. When the inclined face of the projectile discharged from cartridge 63 strikes the projecting surface 64, the projectile forces the pin 66 downwardly and fires cartridge 64, after which it passes outwardly to perforate the casing. Breech block 57 has a similar firing pin 67 pressed downwardly by the projectile from cartridge 64. 70 75

- thus firing cartridge 65. Thus the initial impact on head 60 is effective to cause the cartridges to be discharged in succession. As many barrels as desired may be provided, each barrel having firing mechanism operated by the projectile of the preceding barrel. A fluid tight casing 68 encloses the gun, which is arranged to be guided by a cable or sand line 24, all as in the first form.
- 5 10 When the perforating gun is of sufficiently large diameter it may be formed of two similar halves 70 and 71, as shown in Fig. 7. The barrels 72 in part 70 for example, can be arranged as in Fig. 5, being provided with breech blocks 73. These breech blocks each may be held in place 15 by screws 74 and have firing pins 75, all as before. The arrangement of the bores and breech blocks in the other part 71 is identical; thus when they are assembled, the bores will be inclined in opposite directions. In this form the two parts are 20 to be assembled with the cable 24 in axial space between them, and accordingly each part is in a fluid tight casing 76. The two parts may be conveniently held in assembled relation by screws 78, 25 provided with rubber washers 79, 80 to prevent leakage of the well fluid into the casing about them.
- What is claimed is:
1. In a well casing perforator, a cylindrical body member, and means forming a gun bore having a straight axis oblique to the axis of the body.
- 30 2. In a well casing perforator, a cylindrical body member, means forming a gun bore having a straight axis oblique to the axis of the body, and means forming a breech block adapted to retain a cartridge in said bore.
- 35 3. In a well casing perforator, a cylindrical body member, means forming a gun bore oblique to the axis of the body, means forming a breech block adapted to retain a cartridge in said bore, and firing mechanism associated with the breech block adapted to fire the cartridge, and operable by impact.
- 40 4. In a well casing perforator, a cylindrical body member, means forming a plurality of gun bores oblique to the axis of the body, means forming a breech block for each of the bores to retain a cartridge in the associated bore, firing mechanism supported by each breech block, and means to cause successive actuation of the firing mechanism.
- 45 5. In a well casing perforator, a cylindrical body member, means forming a gun bore oblique to the axis of the body, and means whereby the body may be affixed on a cable to slide axially thereon.
- 50 6. In a well casing perforator, a cylindrical body member, means forming a gun bore oblique to the axis of the body, a cartridge secured in the bore, impact firing mechanism at the end of the body adapted to discharge the cartridge, and a casing enclosing the body to exclude well fluid from the bore and firing mechanism.
7. The method of perforating well casing which comprises, positioning on a line at the point to be perforated a perforator including a cartridge adapted to be fired by impact, placing a similar perforator on said line so as to fall in the casing until it engages the preceding perforator, said engagement serving to fire a cartridge in at least one of the perforators, and placing successive perforators on the line to repeat the operation until the desired amount of perforation is obtained.
- 5 10 8. An adaptor for use with a well casing perforator of the type which discharges a projectile through a bore to penetrate the casing, said adaptor including means providing an extension 15 for said bore.
9. An adaptor for use with a well casing perforator of the type having a gun bore through which a projectile is discharged to penetrate the casing, comprising a member adapted to fit the 20 outside of the perforator and to be attached to the perforator, said adaptor fitting closely the inside of the casing and having a bore adapted to form a continuation of the gun bore.
10. In a device of the character described, a 25 body adapted to be inserted in well casing, said body having a bore for firing a projectile, and a fluid tight covering for the entire body.
11. In a device of the character described, a 30 gun perforator adapted to be inserted in well casing, and adapted to accommodate one or more cartridges, and means adapted to be dropped onto the device from the top of the well casing for providing an impact force detonating said cartridges.
- 35 12. A cartridge for well perforators, characterized by the provision of a projectile having an acute penetrating point, in the form of a tip occurring adjacent the outer edge of the bullet, and all other parts of the projectile being below 40 said tip.
13. In a device of the character described, a 45 body member having a pair of inclined parallel gun bores, the open ends being located on opposite sides of the member, and means for accommodating cartridges in the other ends of the bores.
14. In a device of the character described, a body member having a series of gun bores, the cartridge end of one of a pair of adjacent bores being disposed near the discharge end of the other bore, and a firing device for said cartridge end, and in the path of the projectile passing through said discharge end.
- 50 15. A cartridge for well perforators, characterized by the provision of a projectile that has a penetrating point adjacent the edge of the projectile, and a pair of surfaces sloping transverse to the projectile and defining the point, said sloping surfaces intersecting along a line sloping 55 from the point to the opposite edge of the projectile.
